the output of the filter is small enough for all frequencies, then a frequency detection curve as drawn in FIG. 2 is obtained.

FIG. 4 shows the maximum allowable as a function of the modulating frequency for the crystal used. Crystals having a different band width may show a different graph.

In FIG. 2 the output voltage E of the detector is set out on the vertical axis and the frequency W is set out on the horizontal axis (fully drawn line).

The central frequency coincides with the frequency in the point 12.

The band width of the detector is found between the points 14 and 15 and in the embodiment shown as example it amounts to 2kc./s.

The curve shows only one range for which the control is stable, to wit the part between the points with the abscissas 14 and 15; the intersection point 100 with the control line 13 determining the frequency at which the circuit stabilizes itself.

However, according to the invention a frequency deviation is selected which is considerably larger than the band-width of the crystal and in the embodiment according to FIG. 3 it amounts to 5 kc./s.

These circumstances may give rise to a discrimination curve according to the dotted line of FIG. 2 the parts a and a' forming new stable control reaches.

This is impermissible because a detection curve having a plurality of stable points of intersection with the control line is not unambiguous and, therefore, unsuitable for the precise adjustment of the oscillator, and in order to avoid this the modulation index should be restricted as indicated in FIG. 4.

The control line 13 indicates the value of the control voltage to be supplied to the modulator 1 which is necessary for the change of the central frequency of the signal of the oscillator 2. The control line 13 belongs to a determined frequency deviation of the central frequency of the oscillator. Said frequency deviation is indicated by the distance between the points 12 and 101 which represents the difference in frequency.

When the point 101 is shifted, the control line 13 is shifted with it parallel to itself.

The slope of the control line is inversely proportional to the sensitivity of the modulator circuit.

A detection curve having a plurality of stable points of intersection with the control line is not unambiguous and, therefore, unsuitable for the precise adjustment of the oscillator.

In FIG. 1 a high-frequency amplifier 6 is connected between the oscillator 2 and the detector 3.

The amplifier 6 is mainly used for adapting the detector 3 to the oscillator 2. A direct current amplifier 10 is used for adapting the detector 3 to the modulator 1.

In FIG. 3 the filter 9 which influences the modulation index and which limits the modulation index to the value corresponding to FIG. 4, comprises the resistance 60 and the condenser 61.

The ferrite modulator 16 is provided with a modulation winding 16a, a control winding for the control voltage 16b and a control coil 16c. The control coil 16c is connected to the coil 17 of the oscillator tube 62, which tube is further provided with the requisite adjusting capacitances and resistances in a conventional way.

The coil 26 which is used for drawing the high frequency energy is inductively coupled to the coil 25 in the tuned anode circuit of the tube 62. The tube 62 is further connected to the high frequency amplifier tube 63 which is provided in the anode circuit of an air transformer 67 having a tuned primary winding 35 and a secondary winding 36 with a smaller number of turns.

The winding 36 forms part of the detector circuit 3, in which a crystal 39 is employed as the electromechanical element.

The detector circuit comprises the diodes 37, 38, the 75

crystal 39 already mentioned, the condensers 40, 42 and the resistances 41, 43, 44, 45, 46.

The control voltage is guided back to the control winding 16b of the modulator 1 via a direct current amplifier 10 comprising the tubes 64 and 65 and the resistances 50, 51, 52 and a low pass filter 7 comprising the resistances 55, 56, 57 and 58 and the condensers 53 and 54. Catalogue and data of the elements employed in the embodiment of the invention:

10 Central frequency: 66 MHz; Modulation 150-2500 Hz; Deviation 5 KHz.

Ferrite modulator:

15 Coil 16c 10 turns; 0.45 copper enamel/silk; core material ferroxcube

Coil 16a 400 turns; 0.08 copper enamel

Coil 16b 400 turns; 0.08 copper enamel; core material ferroxcube

Coil 17 11 turns; 1 tap on 4 turns; 0.8 copper enamel/silk

Former of coil 8 mm. diameter

Coil 26 1 turn and Coil 25 7 turns—0.5 mm. copper enamel/silk

Former of coil 6 mm. diameter.

Coil 35 8 turns and Coil 36 2 turns—0.45 mm. copper enamel/silk

Former of coil 6 mm. diameter

¹Variable.

I claim:

1. A device comprising an oscillator, a modulator,

means connecting the output of the modulator to the input of said oscillator, a frequency detector with an electro-mechanical element, which detector is coupled between the output of said oscillator and the input of said modulator, the frequency detection curve of said detector being mainly determined by the properties of the element, and the modulating wave being fed to said modulator by means of a filter which influences the modulation-index, so that the slope of this detection curve does not change its sign more than twice.

2. A device according to claim 1, wherein the frequency detector is a single crystal detector.

3. A device according to claim 1, wherein a high pass filter is connected to the input of said modulator which influences the modulation-index so that the ratio of the frequency deviation to the frequency of the modulating wave above 1500 cycles is less than 0.5.
